UNITED STATES PATENT OFFICE.

FREDERICK S. BLAIR, OF NASHVILLE, TENNESSEE.

APPARATUS FOR DRYING.

SPECIFICATION forming part of Letters Patent No. 508,363, dated November 7, 1893.

Application filed January 27, 1891. Serial No. 379,331. (No model.)

To all whom it may concern:

Be it known that I, FREDERICK S. BLAIR, residing at Nashville, in the county of Davidson and State of Tennessee, have invented an Improved Apparatus for Drying, Handling, and Preserving Grain, Potatoes, Fruit, &c.; and I do hereby declare that the following is a full, clear, and exact description of the invention, which will enable others to make and use the same, reference being had to the accompanying drawings, forming a part of this specification.

My invention relates to improvements in apparatus for drying and preserving grain and seeds while stored in bulk on common floors, in ordinary elevator bins or in the hold of a vessel.

Heretofore grain and seeds when lying in bulk on floors or in elevator bins could be saved from damage only by being frequently moved and exposed to a change of air and even with the constant application of such methods the vitality of the seeds is greatly lessened in even so short a time as one year. The perfect preservation of grain and seeds, for very extended periods of time, requires frequent exposure to fresh dry air and the constant maintenance of a degree of temperature so low as to prevent not only the attacks of insects but the presence of mustiness or other evidences of decay. In many localities the air is frequently so warm and humid as to cause many kinds of grains to rapidly deteriorate. The application of my invention obviates all possibility of damage from such causes.

The object of my invention is to dry the article if damp, or if dry to preserve it sound and sweet with unimpaired vitality for a great length of time without the slightest necessity of moving it while under treatment, and to this end my invention consists in the apparatus which provides for the desiccation and refrigeration of the mass of bulk grain or seeds by means of the liberation and expansion of compressed air in or near the grain or seeds in conjunction with the improved appliances described in this specification.

Figure 1 represents a top plan view of a conical bottomed non-air-tight grain receptacle equipped with perforated induction pipes and compressed air cooling reservoir.

Fig. 2 represents a detail perspective view of perforated induction pipe. Fig. 3 is a top plan view of a series of non-air-tight grain receptacles and of the supply pipe and valves connecting the compressed air cooling reservoir. Fig. 4 is a vertical sectional view of the construction disclosed in Fig. 1.

Similar letters indicate corresponding parts.

In Fig. 1, A is a non-air-tight grain receptacle constructed of any desirable material and preferably in a rectangular shape, having the usual contracted downward inclined bottom X. By non-air-tight it is meant that the receptacle is not adapted to hold air under pressure. In this instance it is represented as having a conical bottom in order that the discharge of the contents through the opening H may be easy and complete when desired.

C is a cooling reservoir for compressed air the same being of any suitable construction and adapted to hold air at such pressure as may be necessary to insure the desired degree of refrigeration when expanded in the contents of the bin A.

D is an induction pipe extending entirely around the inside of and conforming to the rectangular shape of the bin at or a little below the points where the walls and the sloping bottom join. From each section of this pipe, lying upon the inclined surface of the bottom there extend parallel branches or short jet arms d which project in a downward direction toward the center of the bin as shown.

B is a supply pipe adapted to hold air under pressure and connecting the reservoir C at b with the induction pipe D at b' where the latter branches to the right and left.

V is a valve for cutting off the supply of compressed air.

In Fig. 2, F shows the form of perforation deemed preferable in the induction pipe and which is formed by a semi-circular notch cut in the under side of the pipe and F' shows such opening covered with suitable wire cloth of a very fine mesh. The purpose of a very fine mesh is to retard the flow of air and maintain a degree of compression in the supply and induction pipes. This opening should extend along the length of the pipe a distance equal to its diameter, and should cut

into the pipe one half its diameter. The distance between the opening on the pipe should be about equal to the distance between the pipes. This latter distance may be varied 5 anywhere from six inches to two feet or more according to the depth of the grain. It will be observed that by having the openings F, F' cut the same length as the diameters of the pipe branches or jet arms d, and let into 10 said arms half their diameters, extra large outlets are provided for the escape of the compressed air into the bin. It is not necessary to use an induction pipe of large diameter, two inches being sufficient for the largest bins. 15 G is a cap placed over the end of the induction pipe to prevent the exit of air at the end and to cause it to flow uniformly through the openings F. The use of the cap G is to 20 close the end of the pipe and any other device securing that end would answer. The induction pipe should always be so placed as to bring the openings directly at the under side of the pipes thereby allowing no dirt or other obstructive matter to accumulate 25 therein.

The accumulation of dirt, &c., under perforated false bottoms is a great and constant source of annoyance and expense. These 30 troubles are avoided by the use of properly placed induction pipes.

In the operation of my apparatus the air to be applied to the grain or seeds is first compressed by an air-compressor not shown, to a 35 desirable degree of pressure transferred to the cooling reservoir C and while still under pressure it is cooled either by causing it to pass through cold water or preferably through a number of small tubes surrounded by cold water. When the degree of pressure in the 40 reservoir is sufficient the valve V is opened and the air rushes into the induction pipe D and escapes, through the finely meshed wire cloth, into the article under treatment and quickly pervades the entire mass. Compressed 45 air cooled while under pressure rapidly absorbs a great quantity of heat at the point of expansion, and as the grains nearest that point lose their excess heat the expanded air passes them and takes up the surplus heat 50 from the succeeding grains, and so on until in a short time the entire mass is both cool and dry. By this method the temperature of

the grain may very easily and cheaply be reduced to the freezing point, or below if desired, even in the hottest seasons, thereby insuring the perfect preservation of the grain. 55 This operation may be simultaneously applied to a series of bins in direct connection with the reservoir C; but, as often happens, some bin may have in it less than others of 60 the same series, and then it would receive an undue proportion of air. In general it is best to treat the bins successively, as can be shown in Fig. 3. When the contents of bin A have been treated sufficiently, the valves V' and 65 the first V⁴ being opened, and the valves V⁴ of the first bin pipe and V³ being closed the process is repeated in bin A'.

It can be readily seen that all the valves V', V³, V⁴, &c., and the main supply pipe may be 70 dispensed with if the outer end of the main supply pipe is tightly closed. In such event if all the other valves in the bin pipes are kept closed except the valve leading to the bin under treatment, the system will be cheapened and simplified, and equally as effective. 75

A striking advantage of my apparatus is its easy and cheap applicability to any structure ordinarily used to hold bulk grain, requiring as it does no changes further than boring 80 one hole through which to introduce the induction pipe.

Having thus described my invention, what I claim as new, and desire to secure by Letters Patent, is—

In an apparatus of the class described, the combination with a rectangular bin having a contracted conical bottom; of a rectangular frame of induction piping D disposed within the bin at a point directly above the contracted or conical bottom, and having a series of downwardly inclined jet-arms, or branches d, extended inwardly and below the side-portions thereof to conform to the slope of the sides of the conical bottom, said jet arms or 90 branches having screened outlets in their under sides, a compressed air receiver, and a valved supply pipe connected to said receiver and said frame of induction piping, substantially as set forth.

FRED. S. BLAIR.
